FLOOR COVERING

Gerald G. Hunter, Harry M. Pryale, and Samuel C. Clark, Pontiac, Mich., assignors to Baldwin Rubber Company, Pontiac, Mich., a corporation of Michigan

Application November 11, 1935, Serial No. 49,312

1 Claim. (Cl. 154—49)

This invention relates generally to floor coverings and refers more particularly to flexible floor mats of the type employed to cover the flooring of vehicle bodies.

5 One of the principal objects of this invention consists in the provision of a floor mat having a flexible wear resisting covering sheet embossed to provide a recess in the underside of sufficient dimension to receive a resilient pad and having 10 an insulating sheet united to the underside of the padding.

Another advantageous feature of this invention consists in the provision of a floor mat of the character set forth in the preceding paragraph, wherein the covering sheet is provided with a marginal edge portion preformed to lie in the plane of the flooring beyond the recess in the underside of the mat, and wherein the floor engaging surface of the insulating sheet on the 20 underside of the padding lies in a common plane with the corresponding surface of the marginal edge portion of the mat.

The above, as well as other objects, will be made more apparent as this description proceeds, especially when considered in connection with the accompanying drawing, wherein

Figure 1 is a plan view of a floor mat constructed in accordance with this invention;

Figure 2 is a sectional view taken substantially on the plane indicated by the line 2—2 of Figure 1; and

Figure 3 is an enlarged fragmentary sectional view of a portion of the mat shown in Figure 1.

Referring now more in detail to the drawings, 35 it will be noted that there is illustrated in the several figures, a floor mat 10 having a flexible wear resisting covering sheet 11 and having a padding 12 preferably, although not necessarily, permanently secured to the underside of the pad 11. In the present instance, the flexible covering 11 is shown as comprising a sheet of vulcanizable material having an ornamented top surface, and having a marginal portion 13 of suitable width forming a border for the mat.

45 The flexible covering sheet 11 is preferably preformed or vulcanized to the contour thereof shown in Figure 2 of the drawing and, as will be observed from this latter figure, the central or body portion of the covering is embossed during 50 the forming operation to provide a recess 14 in the underside of the covering of sufficient depth to completely receive the padding 12. In other words, the depth of the recess is substantially equal to the thickness of the padding, so that 55 the floor engaging surface of the padding lies in

a common plane with the floor engaging surface of the marginal portion 13, and this is desirable since it permits the marginal portion to lie flat upon the flooring covered by the mat.

The padding 12 is of such a nature as to form 5 a highly resilient foundation for the flexible covering sheet 11, and the height of the embossed portion is predetermined to permit the use of a padding sufficiently thick to impart the desired soft yielding tread to the mat. In detail 10 the padding 12 comprises a layer 15 of fibrous material and an insulating sheet 16 forming a backing for the layer 15. As will be observed 15 from Figure 3, the layer 15 of fibrous material is relatively thick and the material from which the same is formed is selected to not only impart maximum resiliency to the tread on the mat, but to also afford an efficient insulation against sound and heat. The backing sheet 16 is preferably formed 20 of rubber and not only assists the layer 15 in effectively insulating the mat against the passage of heat and sound therethrough, but in addition, serves to weatherproof the fibrous material to a certain extent. In order to provide an integral 25 mat construction, the layer of fibrous material 15 is permanently secured to the underside of the embossed portion of the flexible sheet 11 and the backing 16 is permanently secured on the underside of the fibrous material, so as to engage the 30 flooring adapted to be covered by the mat.

For the purpose of illustration, the floor mat is featured in association with the driver's compartment of a motor vehicle and accordingly, the mat is suitably apertured at predetermined points for the passage of the various vehicle controls 35 therethrough. Upon reference to Figure 2, it will be noted that the apertures through the mat are also provided with marginal edge portions adapted to engage the flooring in such a manner as to conceal the padding 15.

40 Thus, from the foregoing, it will be observed that we have provided a floor mat possessing a highly resilient tread and presenting a neat and pleasing appearance. It will also be apparent that the layer of fibrous material affording the 45 resilient tread is protected from direct engagement with the flooring by a sheet of material impervious to moisture and possessing heat and sound insulating qualities. Thus, the ability of the mat to afford the desired insulation against heat and sound is not only materially increased but 50 the durability of the mat is also enhanced.

55 What we claim as our invention is:

A floor mat having a layer of fibrous material of predetermined area, an elastic base layer in-

cluding rubber secured to and coextensive with one face of the layer of fibrous material, said base layer constituting the floor engaging surface, and a preformed cover of wear-resisting material of 5 uniform thickness and of greater area than the layer of fibrous material secured to the other face of the layer of fibrous material and having marginal portions free of the fibrous material

and base layer extending downwardly beyond the upper edges of the layer of fibrous material for surface engagement with the floor at points substantially in a horizontal plane with but spaced from the lower edges of the base layer. 5
